CENTRIFUGAL METAL CASTING PROCESS AND MOLD APPARATUS

Clarence K. Johnson, Portland, Oreg., assignor, by mesne assignments, to Electric Steel Foundry Company, Portland, Oreg., a corporation of Oregon

Application July 2, 1954, Serial No. 441,022

14 Claims. (Cl. 22—65)

This invention relates to a centrifugal metal casting process and mold apparatus. The invention is particularly useful in the casting of a large number of individual castings within a single annular mold, but has other applications.

One of the basic problems in centrifugal casting of metal has been to control the metal as it is poured into the mold so as to prevent the metal from rushing through the length of the mold in an irregular fashion producing laps, metal inclusions, cold shuts, etc. Various methods have been suggested as a means for retarding the flow of metal and otherwise preventing such undesired results, but such methods have not solved the problem.

An object of the present invention is to provide a method and means for restraining the flow of metal until certain desired conditions have been reached, and then releasing the metal in a form in which an even distribution on the inside diameter of the casting is obtained so as to cast an uneven contour on the inside diameter of the casting. Another object is to provide assembled cores in combination with a control core whereby the flow of metal is retarded and a uniform casting of a contour on the inside diameter is obtained. Yet another object is to provide a combination of cores arranged in such a manner as to control the flow of metal along the inside diameter of the cores while at the same time filling radial recesses within the cores, the feed being in the form of an annular stream which progresses substantially and uniformly within the cores, thus avoiding the formation of laps, metal inclusions, cold shuts, etc. A further object is to provide a control core in which the passages are provided with an angle to give a pump effect, thereby increasing the efficiency of the operation. A still further object is to provide the initial mold ring, which receives the inrush of metal of abrasion-resisting material, whereby erosion at this point will be avoided. Other specific objects and advantages will appear as the specification proceeds.

The invention is shown, in an illustrative embodiment, by the accompanying drawing, in which—

Figure 1 is a broken, longitudinal sectional view showing the arrangement of cores within the mold embodying my invention, while also illustrating the process of my invention; Fig. 2, a side view in elevation of the united castings formed in the process; Fig. 3, a front view in elevation of a casting produced in the process; Fig. 4, a front face view in elevation of the control core which may be employed; and Fig. 5, a sectional view, the section being taken as indicated at line 5—5 of Fig. 4.

In the illustration given, 10 designates a metal mold having bearing portions or tires 11 supported by the usual wheel bearings 12. The outer end of the mold 10 is provided with a flared mouth portion 13 adapted to receive a closure plate 14 apertured centrally at 15, the plate being adapted to be secured in position by wedges 16. Since the foregoing is well known structure, a detailed description herein is believed unnecessary. It

2

will be understood that any type of centrifugal mold apparatus may be employed in the practice of the present invention.

Within the flared portion 13 of the mold, I secure 5 an end core 17 provided with a central opening aligned with the opening 15 of the closure plate and abutting an elongated annular core 18. At the other end of the annular core 18, I provide a control core 19. If desired, any or all of the cores may be provided with interlocking ribs and grooves. The core 19 is provided with a series of spaced openings 21, which may be of any designed number and of any size diameter. By way of example, in the mold shown, the core 19 is one inch thick and there are six openings 21 of one-half inch diameter. It will be understood that any number of peripheral openings 21 may be employed for controlling the flow of metal inwardly into the mold along the inner periphery of the cores therein.

Inwardly of the control core 19 are a plurality of molding cores 22. Each of the cores 22 is supported within a metal ring 24, as shown more clearly in Fig. 1, and is provided with a radial recess 25. In the specific illustration given, the recess 25 has a radial portion, indicated by the numeral 26, and a horizontal portion, indicated by the numeral 27.

The usual pouring cup 28, formed of molding sand, or the like, is supported in position for introducing molten metal 29 into the inlet opening of the mold.

It will be understood that at the opposite end of the mold (not shown), there is an end core and closure plate similar to those shown as members 17 and 14, respectively, except that the hole is smaller. Such an end core and closure plate keep the metal from flowing out of the end opposite the pouring end while permitting the escape of mold gases.

The control core 19 is preferably provided with a central opening 30 which serves to release gases that are generated by the combustion of the core sands. Further, I prefer to form the first ring 20 adjacent the control core 19 with means for resisting abrasion caused by the initial surge of eroding metal. The first ring 20 is preferably made of extra hard core sand which is able to receive the initial surge of eroding metal without erosion by the inrush of this initial metal. It will be understood that any suitable means for increasing the abrasion resistance of the first ring 20 may be employed.

The passages or openings 21 through the control core 19 may be horizontal or of any desired contour. I prefer, however, to angle the holes so as to give a pump effect and thus cause metal to be sucked through the holes instead of relying on mere horizontal flow. As shown more clearly in Figs. 4 and 5, the holes or passages have been given an angle of about twenty degrees, which is found to give an effective pump effect. I have employed an angle away from the horizontal of from zero to forty-five degrees with excellent results.

The core layout as set out in the drawings is effective in filling uniformly one cavity at a time and thus keeping the metal from "dancing over" to the next core and then later filling up, thus forming laps and cold shuts, but a primary and important object and result is to contour the internal diameter of the rings with their radial and horizontal recesses.

The molding cores may, of course, be of any desired shape or form so as to produce rings or other castings which are preferably united by riser metal which may be removed later by machining or other means. In Fig. 2, a stick of castings is shown in the form that they are produced by the molding core structure shown in Fig. 1, the outer ring structure being indicated by the numeral 30, the inner annular flange being indicated by the numeral 31, and the riser metal connecting the rings being shown

by the numeral 32. In the specific form illustrated, I cast lugs 33 upon the inner structure of the ring. The showing, however, is for the purpose of illustration, and it will be understood that any molding cores providing the desired radial recesses for reception of the metal may be employed.

Operation

In the operation of the process and structure shown, molten metal 29 is poured into the cup 28, which is supported upon a stationary support (not shown) for discharging metal into the rotating mold 16. The mold 16 is rotated by mechanism (not shown) in the usual manner to attain a rotational speed causing the metal as it enters to form an annular reservoir 34 within the chamber formed between the control core 19 and the inlet core 17. The control core 19 thus restrains longitudinal flow of the metal 29 until the depth of the annular reservoir 34 covers the openings 21. The metal then flows through the openings 21, which are preferably angled and distributed at spaced distances along the peripheral portion of core 19 within the reservoir chamber, and advances along the interior of the cores 22. The pumping action of the control core increases the efficiency of the operation and brings about an even, steady flow of metal along the internal diameter of the cores. The radial recesses within the cores 22 are filled individually as the metal progresses and exert a retarding and regulating influence upon the flow of the metal. As a result, it is found that a uniform contour is cast on the inside diameter of the castings, without metal inclusions, cold shuts, laps, etc.

In Fig. 1, the progress of the metal during the pouring operation is illustrated, a rather uniform reservoir of uniform thickness being maintained in the reservoir chamber between cores 17 and 19. A thin annular stream of metal flows past the control core 19 and longitudinally of the composite cores 22, the radial recesses 25 serving to retard and control the flow of the metal past the various cores 22. In this manner, it is found that an inside diameter contour is formed on the castings and the riser metal between the ring castings may later be cut away to form the separate rings.

In the foregoing operation, it will be noted that I require four cores, namely, the inlet core 17 having a central opening for receiving the metal from the cup 28, a sleeve or annular core 18 forming a reservoir, the control core 19, and the abrasion core 20. The openings 21 in the control core 19 may be circular, rectangular, elliptical, or of any suitable or desired shape.

In the foregoing operation, the provision of the reservoir at one end of the mold cavity, in combination with the peripheral openings 21 in the control core 19, allows the metal, which has gained the same peripheral speed as that of the mold, to proceed evenly through the full length of the cavity, the radial recesses of the individual molding cores 22 providing spaced retarding means controlling the flow of the metal. Also, the structure serves to keep the metal from skipping partially to the next core and then filling up later, thus causing laps and cold shuts.

After the casting has been formed, the wedges 16 may be removed and the endplate 14 and cores 17, 18 and 19 removed. A long metal bar may be passed through the castings and drawn outwardly to remove the stick of castings illustrated in Fig. 2. In this operation, the cores 22 are usually disintegrated and the spaced outer rings 24, which aid in the breaking up on the cores 22, may be removed. The connecting riser metal 32 may then be severed, as already stated, to free the separate ring castings or other types of castings which are formed in the process.

While in the foregoing specification I have set forth in considerable detail a specific process and core arrangement for the purpose of illustrating my invention, it will be understood that such details may be varied

widely by those skilled in the art without departing from the spirit of my invention.

I claim:

1. In a centrifugal casting process for forming a casting in a mold, in which process molten metal is poured into a mold mounted for rotation and the mold rotated about an axis to form a casting, the steps of mounting within said mold an annular core having radial recesses therein, pouring the molten metal into one end of the mold, restraining the longitudinal flow of the metal in said end of the mold until the metal has attained the peripheral speed of the mold, and then releasing the metal in a thin annular stream along the inside diameter of the core.
15. In a centrifugal casting process in which molten metal is poured into a mold mounted for rotation and the mold rotated about an axis to form the casting, the steps of introducing a plurality of annular cores into the mold to form radial recesses, pouring the molten metal into one end of the mold while rotating the mold, substantially restraining the flow of the metal in said end of the mold until the metal has attained the peripheral speed of the mold, and then releasing the metal in a thin annular stream along the inside diameter of said cores.
20. The process of claim 2, in which the metal is released through spaced passages inclined from the horizontal.
25. The process of claim 2, in which said radial recesses have grooves in communication with said radial recesses.
30. The process of claim 2, in which the molten metal is fed at spaced intervals along the inside diameter of said cores.
35. In combination with a centrifugal mold mounted for rotation and having a central inlet opening at one end and means for introducing molten metal into said opening while the mold is operating, a core mounted within said mold and having a radial recess therein, and a control core adjacent said molding core and spaced from the inlet of said mold to provide a reservoir, said control core having a plurality of openings aligned generally with the inside diameter of said core.
40. The structure of claim 6, in which said openings in the control core are spaced slightly inwardly of the inside diameter of said core.
45. In combination with a centrifugal mold mounted for rotation and having a control opening in one end and means for introducing molten metal into said opening while the mold is rotating, a plurality of mold cores supported within said mold and providing spaced radial recesses, and a control core adjacent said molding cores and spaced from the inlet of said mold to provide a reservoir, said control core having peripheral passages therethrough generally aligned with the inside diameter of the cores.
50. The structure of claim 8, in which the peripheral passages of the control core are inclined from the horizontal within a range of between zero and 45°.
55. The structure of claim 8, in which the peripheral passages of the control core are inclined from the horizontal by about 20°.
60. In combination with a centrifugal mold mounted for rotation and having a closure plate at one end provided with a central opening and means for introducing molten metal into said opening, an inlet core having an opening aligned with the opening in said closure plate, a sleeve core received within said mold and engaging at one end said inlet core, a control core engaging the other end of said sleeve core, and a mold core on the opposite side of said control core and having radial recesses, said control core having a plurality of spaced openings generally aligned with the inside diameter of said mold core.
65. In combination with a centrifugal mold mounted for rotation and having a closure plate at one end provided with a central inlet opening and means for introducing molten metal into said opening while the mold is rotat-

ing, an inlet core secured across the end of said mold by said closure plate, a sleeve core within said mold and abutting said inlet core, a control core abutting the other end of said sleeve core, said control core having spaced annular openings therethrough, a plurality of mold cores having radial recesses therein, and rings within said mold and separately supporting said mold cores.

13. Mold apparatus, comprising a centrifugal mold mounted for rotation and having at least at each end a closure plate and inlet core, each provided with an inlet opening for receiving molten metal while the mold is rotating, a sleeve core within said mold and abutting said inlet mold, a control core abutting the other end of said sleeve core, said control core having spaced annular openings therethrough and having also a central opening, a plurality of mold cores having radial recesses therein, and rings within said mold and separately supporting said mold cores.

14. Mold apparatus, comprising a centrifugal mold mounted for rotation and having at least at each end a closure plate and inlet core, each provided with an inlet opening for receiving molten metal while the mold is rotating, a sleeve core within said mold and abutting said inlet mold, a control core abutting the other end of said sleeve core, said control core having spaced annular openings therethrough, and a plurality of mold cores having radial recesses therein, one of said mold cores abutting said control core being formed of erosion-proof material.
